United States Patent

Des. 238,476
Patented Jan. 20, 1976

238,476

TRAY

Leland H. Logue, 150 S. Marion Parkway,
Denver, Colo. 80209

Filed Apr. 19, 1974, Ser. No. 462,261

Term of patent 14 years

Int. Cl. D7—99

U.S. Cl. D7—20

FIG. 1 is a perspective view of a tray showing my new design;

FIG. 2 is a top view thereof;

FIG. 3 is a bottom view thereof;

FIG. 4 is a side elevational view thereof; and

FIG. 5 is another side elevational view thereof.

I claim:

The ornamental design for a tray, as shown.
